UNITED STATES PATENT OFFICE

THOMAS J. KING, JR., OF CHICAGO, AND IVAN H. SPOOR, OF BERWYN, ILLINOIS, ASSIGNORS TO THE GERRARD COMPANY, INC., OF CHICAGO, ILLINOIS, A CORPORATION OF DELAWARE

WIRE HOLDER

Application filed October 12, 1928. Serial No. 312,181.

The principal object of the invention is to provide a novel holder for a coil of wire which will uncoil the wire as fast as needed, will not allow the wire to kink, knot or tangle while being uncoiled, and will direct the end of the wire into a position wherein it may be conveniently grasped.

Another important object of the invention is to provide a wire holder of the type described which is inexpensive to manufacture and may be easily moved from one place to another.

Other objects and advantages of the invention will be evident upon a full understanding of the construction, arrangement and operation of a wire holder embodying the invention.

One form of the invention is presented herein for the purpose of exemplification, but it will of course be appreciated that the invention is susceptible of embodiment in other structurally modified forms coming equally within the scope of the claims.

In the accompanying drawings:

Fig. 1 is a side view of a wire holder constructed in accordance with the invention;

Fig. 2 is a plan view of the same; and

Fig. 3 is a vertical section, taken on the line 3—3 of Fig. 1.

The wire holder of the invention is characterized by a stationary frame and a movable rider. The frame supports the coil of wire in a horizontal position, and the rider directs one end of the wire upwardly from the center of the frame into a position wherein it may be conveniently grasped. When the upwardly directed end of the wire is pulled, the rider revolves on the frame and uncoils the wire.

The frame includes a horizontally disposed ring-shaped member 10 which is made up of a central spider 11, a plurality of radiating spokes 12, a rim 13 and a plurality of feet 14 on the bottoms of the spokes near the rim. A post 15 is secured to and projects upwardly from the spider 11, and a number of coil-positioning brackets 16 are secured to and project upwardly from the spokes 12. The coil of wire 17 to be unwound is placed on the member 10 and is centered thereon by

the brackets 16, which brackets are adjustable toward and away from the post 15 to accommodate coils of different sizes. The frame also includes a horizontally disposed ring-shaped member 18 which is of smaller diameter than the member 10 and is arranged in concentric vertically spaced relation to the same. The member 18 is made up of a central spider 19 which is secured to the post 15, a plurality of radiating spokes 20 and a rim 21.

The rider consists of a hub 22, which is journaled on the upper end of the post 15 above the member 18, an upwardly flared bell-shaped wire guide 23 which is supported above the hub 22 on side rods 24 in axial alignment with the post 15, and a horizontally disposed ring-shaped wire guide 25 which is supported from the hub 22 outwardly of the member 18 on radially extending 70 and downwardly curved side rods 26.

One end of the wire 17 from the coil 18 is threaded upwardly through the ring-shaped guide 25 and then upwardly through the bell-shaped guide 23, which latter guide serves to direct the end of the wire upwardly into a position wherein it may be conveniently grasped. When the upwardly directed end of the wire is pulled to remove some of the wire from the coil, the hub 22 of the rider 75 will automatically rotate on the post 15 of the frame and the ring-shaped guide 25 of the rider will travel about the periphery of the frame and uncoil the wire as fast as it is pulled through the bell-shaped guide 23 of 80 the rider.

The relative arrangement and mounting of the wire guides 23 and 25 prevents the wire from kinking, knotting or tangling 85 while being uncoiled. When the coil of wire 17 has been used up, a new coil may be positioned in the frame by merely lifting the hub 22 of the rider up off of the post 15 of the frame, loosening the set screw or other means used to secure the upper member 18 of the frame to the post, and lifting such member 90 up off of the post.

The upper frame member 18 serves to prevent any of the loops in the coil from working 100 upwardly on the brackets 16 beyond said

member, while the feet 14 on the bottom of the frame member 10 serves to prevent any of the loops in the coil from working under that member. In order to move the wire holder from one place to another, it is merely necessary to tilt it up onto the large rim 13 and roll it along on that rim.

We claim:

1. In a wire holder, a stationary frame for supporting a coil of wire in a horizontal position, and a guide which is revolvable about the center of the frame and is provided with upwardly directed openings adjacent both the center and the periphery of the frame 15 through which the wire passes in being uncoiled, said peripheral opening being a substantial distance below the level of said center opening whereby to permit the wire to curve gradually from the coil first through 20 the peripheral opening and then through the center opening.

2. In a wire holder, means for supporting and confining a coil of wire, and means for automatically uncoiling the wire when one 25 end of the wire is pulled, said last mentioned means consisting of a rider journaled on the upper portion of said supporting means and extending laterally to a point adjacent the periphery of the same, an upwardly directed 30 wire guide on the rider above the upper portion of said supporting means, and another upwardly directed wire guide on the rider a substantial distance beneath and to one side of the first mentioned guide adjacent the periphery of said supporting means.

3. In a wire holder, a stationary frame for supporting a coil of wire in a horizontal position, and means for automatically uncoiling the wire when one end of the wire is 40 pulled, said last mentioned means consisting of a rider rotatably mounted on the frame at the center of the same and extending laterally to a point adjacent the periphery of the frame, an upwardly flared bell-shaped wire 45 guide on the rider above the center of the frame, and another horizontally disposed ring-shaped wire guide on the rider adjacent the periphery of the frame a substantial distance below the level of the lower end of the 50 center guide.

4. In a wire holder, a stationary frame for supporting a coil of wire, and means for automatically uncoiling the wire when one end of the wire is pulled, said frame consisting of 55 a horizontally disposed ring-shaped frame member, a post secured to and extending upwardly from the center of said frame member, another horizontally disposed ring-shaped frame member of smaller diameter 60 detachably secured at its center to said post in vertically spaced relation to the first mentioned frame member, and radially adjustable brackets carried by the lower frame member for centering a coil of wire positioned 65 therebetween, said brackets being adjustable

independently of said second ring-shaped frame member.

5. In a wire holder, a horizontally disposed ring-shaped frame member, a post secured to and extending upwardly from the center of said frame member, another horizontally disposed ring-shaped frame member of smaller diameter secured at its center to said post in vertically spaced relation to the first mentioned frame member, means for centering a coil of wire positioned between said frame members, and a rider journaled on the upper end of the post above the upper frame member and extending laterally to a point beyond the periphery of the same, said rider having an upwardly flared bell-shaped wire guide above the upper end of the post in axial alignment therewith and a ring-shaped wire guide outwardly of the periphery of the upper frame member in substantially the plane of the latter.

In testimony whereof we have hereunto subscribed our names.

THOMAS J. KING, JR.
IVAN H. SPOOR.
